UNITED STATES PATENT OFFICE.

EMMA E. BOWER, OF ANN ARBOR, MICHIGAN.

DESIGN FOR A BADGE.

SPECIFICATION forming part of Design No. 37,117, dated September 6, 1904.

Application filed August 15, 1904. Serial No. 220,866. Term of patent 7 years.

To all whom it may concern:

Be it known that I, EMMA E. BOWER, a citizen of the United States, residing at Ann Arbor, in the county of Washtenaw and State of Michigan, have invented a new, original, and ornamental Design for a Badge, of which the following is a specification, reference being had to the accompanying drawing, forming part thereof.

10 The figure is a plan view of a badge, showing my new design.

What I claim as new, and desire to secure by Letters Patent, is—

The ornamental design for a badge, as shown.

EMMA E. BOWER.
